COMBINATION CANE AND UMBRELLA

George C. Henderson, San Antonio, Tex.

Application June 26, 1939, Serial No. 281,289

4 Claims. (Cl. 135—17)

This invention relates to a combination cane and umbrella, and has for one of its objects the production of a simple and efficient means for encasing the folds of an umbrella to protect the umbrella when in a folded or closed position, and also presenting a neat appearance while the combination cane and umbrella is being used as a cane or walking stick.

A further object of this invention is the production of a handle structure which constitutes a casing for a cigarette case, cigarette lighter, batteries, globe and lens for an electric flash light, a drinking cup, magnifying glass, and container for miscellaneous objects, and means associated with the handle for supporting a metal fishing rod or tip, an umbrella and enclosure therefor, and a camera-supporting means.

Other objects and advantages of the present invention will appear throughout the following specification and claims.

In the drawings:

Figure 1 is a side elevational view of the combination cane and umbrella, a portion of the umbrella enclosure being shown in section;

Figure 2 is an enlarged horizontal sectional view taken on line 2—2 of Figure 1;

Figure 3 is a side elevational view of the combination cane and umbrella in a set-up position where the same may be used as a tripod for a camera;

Figure 4 is an enlarged vertical sectional view of the device with certain parts broken away and showing the umbrella partly opened;

Figure 5 is a side elevational view of the device showing the umbrella in an open position and partly in section and the concave tripod legs and enclosures in an extended position;

Figure 6 is a view of the device showing the device assembled to provide an umbrella;

Figure 7 is a horizontal sectional view taken on line 7—7 of Figure 1;

Figure 8 is an enlarged vertical sectional view of the lower end of the staff of the device when the parts are in a closed position;

Figure 9 is a similar view showing the fishing rod attached to the end of the staff;

Figure 10 is a perspective view of the handle with the cover portion in a partly open position; and

Figure 11 is a longitudinal section of the handle.

By referring to the drawings, it will be seen that 10 designates the handle which is threaded upon the staff 11, as at 12. The handle 10 is provided with a horizontal portion 13, which

terminates in a depending neck 14 upon the lower end of which is threaded a hollow knob 15 constituting a drinking cup, when detached from the handle 10. The lower portion 16 of the knob 15 constitutes a magnifying glass. A cigarette lighter 17 is carried within the depending neck 14 and a cigarette container 18 is carried within the handle 10, as shown in Figure 11. A horizontal tray 19 is formed in the horizontal portion 13 for receiving miscellaneous articles. A hinged cover 20 is adapted to close the top of the handle 10, and this cover 20 carries a ruler 21 calibrated in inches, and a mirror 22 extends from the end of the ruler 21. The mirror 22 is provided with a Celluloid under face 23 which may be used, if desired, as a memorandum pad. A retractile screw 24 is threaded through the cover 20 near the inner end thereof and is normally in the position shown in Figure 11, but may be extended to the position shown in Figure 10 to provide a camera attachment when the cane is used as a tripod. The mirror 22 is preferably slidable under the ruler 21.

A series of batteries 25 is carried within the staff 11 and the batteries contact with a bulb 26 which is actuated by a switch button 27. A light projecting lens 28 is carried by the staff 11 adjacent the bulb 26, the lens 28 being preferably placed in the mouth of a designed face 29 formed upon the staff 11 and glass eyes 30 may be formed in the staff 11 to simulate eyes and these eyes are preferably red in color.

The staff 11 is provided with a hollow shank portion 31 in which is frictionally and slidably mounted an adjustable rod 32 upon the lower end of which rod 32 is secured in a conventional manner a foldable umbrella 33 having the conventional ribs and braces 34. A hollow cup 35 is carried by the lower end of the rod 32 adjacent the umbrella portion 33, as shown in Figures 5 and 6, and the outer terminal of the rod 32 constitutes an extension 36. A metal fishing rod 37 fits longitudinally within a longitudinal bore formed within the rod 32, as shown in Figure 4, and is provided with a threaded portion 38 threaded in one direction, and a threaded portion 39 threaded in the opposite direction separated by a nut or disc 40. When the rod 37 is not in use it is threaded into position shown in Figure 4, but when it is desired to use the rod it is threaded into the lower end of the extension 36 in the position shown in Figure 9.

A series of tripod legs 41 are hingedly secured to the handle 11 by means of the shank portions 42, as shown in enlarged detail in Figure 4, and

Figure 7, and these tripod legs 41 are preferably concavo-convex in cross-section and constitute a trisection metal tube when in a closed position which completely encircles the umbrella 33 in the 5 manner shown in Figure 2. A retaining cup 43 is carried by the extension 36 just below the lower end of the umbrella 33 and a cap 44 is threaded upon the extension 36 to retain the cup 43 in position, the cup 43 being adapted to receive the 10 ends of the tripod legs 41 in the manner shown in Figure 8 and hold the legs 41 in an assembled position such as is shown in Figures 1 and 2, whereby the device may be used as a cane, the umbrella 33 being completely encased within the 15 concavo-convex tripod legs 41.

When the device is to be used as an umbrella, the tripod legs 41 may be swung to the position shown in Figure 6, and the lower ends of these 20 legs are then fitted within the cup 35, the legs being provided with suitable notches 41a to fit around the braces 34. The assembly may be easily made due to the fact that the rod 32 is 25 slidably mounted within the hollow shank portion 31, to move the cup toward and away from the ends of the legs 41. The notches 41a are of sufficient size to permit of this adjustment, the movement being very slight.

If desired, the legs 41 which constitute encasement members may be provided with overlapping 30 beveled adjoining edges to compensate for the different positions of the legs or encasement members 41 when in an umbrella-encircling position, as shown in Figures 1 and 2, or in a staff-encircling position as shown in Figure 6.

35 It should be understood that a very simple and efficient means has been provided whereby a very neat appearing umbrella encasing shield in the nature of the concavo-convex legs 41 is produced.

Further, it should be understood that the rod 40 32 is frictionally slidable within the hollow shank portion 31 and is adapted to be held in a firm position when once adjusted, but at the same time may be moved under a proper degree of pressure.

Certain detail changes in the mechanical construction 45 may be employed without departing from the spirit of the invention, so long as such changes fall within the scope of the appended claims.

Having described the invention what is claimed 50 is:

1. In combination with a cane shank, a foldable umbrella carried by the shank and movable to and from extended and folded positions, encase-

ment members hingedly secured to the shank and adapted to encase the umbrella when the umbrella is in a folded position, a means engaging the ends of the encasement members for holding the encasement members in snug assembled relation to provide a neat appearing casing for the foldable umbrella, said encasement members being concavo-convex in cross-section, and said encasement members having means for accommodating the braces of an umbrella when the umbrella is in an extended position and when the encasement members are in an assembled position. 5 10

2. In combination with a cane shank, a foldable umbrella carried by the shank and movable to and from extended and folded positions, encasement members hingedly secured to the shank and adapted to encase the umbrella when the umbrella is in a folded position, said shank having an extension, a cap carried by the extension and 15 adapted to receive the ends of the encasement members, and a cap threaded upon said extension for clamping said cup in locking engagement with the ends of said encasement members. 20

3. In combination with a cane shank, a foldable umbrella carried by the shank and movable to and from extended and folded positions, encasement members hingedly secured to the shank and adapted to encase the umbrella when the umbrella is in a folded position, said cane shank having a frictionally adjustable extension section, a cup carried upon the extensible portion of the shank adjacent the umbrella and adapted to receive the ends of the encasement members for holding the encasement members snugly around the shank, and the cup carried by the adjustable portion of the shank being movable into clamping engagement with the ends of the encasement members. 25 30 35

4. In combination with a cane shank, a foldable umbrella carried by the shank and movable to and from extended and folded positions, encasement members anchored against longitudinal movement upon said shank and adapted to encase the umbrella when the umbrella is in a folded position, and means slidably mounted upon the outer end of said shank and movable toward and away from the outer ends of the encasement members for engaging the outer ends of the encasement members to hold said members in assembled relation and provide a neatly appearing casing for the folding umbrella. 40 45 50
